UNITED STATES PATENT OFFICE

2,239,355

LABEL PRINTING AND ACCOUNTING
MACHINE

Harmon P. Elliott, Watertown, Mass., assignor to
The Elliott Addressing Machine Company, a
corporation of Massachusetts

Application April 2, 1940, Serial No. 327,425

31 Claims. (Cl. 101—58)

This invention relates to a machine of the general type shown and described in U. S. Patent 2,015,552, granted to me September 24, 1935, for printing and addressing wrappers, designed primarily for use in the free distribution of catalogues and like publications sent out to induce purchase and promote trade.

The present machine, like the machine of the patent, is designed to print addresses, but here the addresses are applied to label blanks which, while not differing materially from the wrappers of the patent, are used by literary guilds, book clubs and like organizations in periodically shipping books and other publications to members or subscribers on charge accounts and the main departures from the patent are, first, in adapting the machine to do the major portion of the accounting work on the stencils from which the addresses are printed, to avoid the necessity and cost of keeping book accounts; second, in utilizing the stencil account formation to control the various machine operations in the passage of the stencils through the same; and third, in producing an account formation upon the stencil from which responsive machine action is obtainable to print a complete statement of the account, dated, addressed and in itemized amounts.

In the present embodiment of the invention, the machine acts automatically to record on the address bearing stencils passing through the same, debit entries, in code form, representing charges against the addresses for the books sent them and so positions the entries as to indicate the dates of shipment of the books. To make the accounts complete on the stencils, entries for current book offers refused and credit entries for books paid for, or returned, are recorded thereon by hand.

In printing labels, the machine is adapted to distinguish between good and bad accounts, being guided by the recorded debit and credit entries on the address bearing stencils, to limit the printing to labels for the good accounts only, rejecting the bad account stencils and sorting them out for billing or other appropriate action by the collection department of the business.

In the present embodiment of the invention, the debit and credit entries of the stencil accounts preferably take the form that permits electric circuits to be completed through them, which act to effect appropriate machine operation according to the condition of each addressee's account.

To simplify the machine action, the entries on the stencils are made in simple code form, such for example, as a round or other shaped mark,

which may be of electrically conductive ink printed on the stencil, or of thin sheet metal, stapled to the stencil, but, to meet practical requirements to greater advantage, a punched hole is preferred, through which a metallic circuit is completed for the passage of electric currents, for the purpose above stated.

To accommodate and give definite meaning to these code signs, to which the machine will respond by appropriate action and which may be read at a glance, the frame of the stencil is extended above the address panel to receive the punched openings and is charted to represent an account form, with debit, credit and other space markings, to indicate the character of the punched entries therein.

Thus it will be seen that in addition to forming a complete and permanent account record on the address stencil of each club member or subscriber, the punched holes serve the important purpose of enabling circuits to be completed through them to permit or prevent certain operations of the machine.

II, for example, a member or subscriber has exceeded a set limit of credit, as shown by the debit entries, and the absence of offsetting credits, the machine will be pre-set by the circuits completed through the openings, for non-print, as to this stencil. That is to say, no address label will be printed from the stencil as it passes through the machine and as the printed address label is the sign to the shipping department to send a book to the addressee, there will be no shipment to that subscriber and no charge entered and the only action of the machine on the stencil will be to sort it out and deposit it in a special hopper provided for delinquent accounts.

If, on the other hand, the limit of credit has not been exceeded, again as shown by the account formation on the stencil, the circuit completed through the openings will permit normal operation of the machine, which is to print an address label, punch a debit charge opening in a dated space of the stencil from which the label is printed, and deposit the stencil in a hopper for good accounts, at the end of its passage through the machine.

In the same manner as above described, the machine may be pre-set by the account formation to print labels and record additional entries for the shipment of other than current books and position such entries in the account form of the stencil, to indicate whether or not a charge is made for the book.

If no charge is to be made, as for bonus books, sent free to subscribers whose accounts have been in good standing for a period of say, six months, the machine will distinguish, as above described, between good and bad accounts, by the action of the circuits completed through the openings in the stencils and limit the printing of labels for the shipment of bonus books, to the good accounts only.

Before the stencils are run through the machine to print labels for the shipment of bonus or other books, sent free of charge, a blank stencil of orange or other selected color, having a specially positioned hand-punched hole in the margin thereof, is placed in the stack above the address stencil of each member whose credit showing in the stencil account entitles him to such a book. In the run of the stencils through the machine, the circuits completed through the marginal hole in the blank orange stencil, will pre-set the machine to print, punch and deposit the address stencil it follows in the good account hopper and deliver the orange stencil to the discard or delinquent hopper.

In like manner, when extra charges appear, hand-entered, on the address stencil of a member or subscriber, a black, or other colored stencil, blank as to name and address, but having a hand-punched opening specially positioned therein, is placed in the stack above each of such address stencils, and the circuits completed through the openings of the stencil and its markers will preset the machine first for operation according to the condition of the stencil account and then for non-printing the black marker and depositing it in the same hopper with the address stencil for the attention of the billing department.

The machine, above referred to, that utilizes the present account formation of the stencils for printing addressed statements, in itemized amounts, has been made the subject of a separate application and will not, therefore, be further described.

It will be apparent from the disclosure herein that the machine is adaptable to serve purposes other than as an aid in conducting the business of a literary guild or like organization and may be used to equal advantage in any field in which there is periodic shipment of articles on charge accounts or of which a reference record is desired.

The accompanying drawings will serve to illustrate a machine suitable for carrying my invention into effect, but I do not wish to be understood as intending to limit myself to either the exact form or details of the mechanism shown, as various changes may be made therein without departing from the spirit and scope of the invention as outlined in the appended claims.

In the drawings—

Fig. 2 is a like view, on an enlarged scale, of a portion of the machine, showing the adjustable punch-carrying member and the mechanism for opening and closing the discard or delinquent hopper.

Fig. 3 is an enlarged detail sectional view, on the line 3—3 of Fig. 1, showing the mechanism of Fig. 2, in elevation and partial section.

Fig. 4 is a cross section on the line 4—4 of Fig. 1, through the discard or delinquent hopper, showing the mechanism for opening and closing the same.

Fig. 5 is a detail sectional view on the line 5—5 of Fig. 1, showing the ratchet feed for the

timing device of the opening mechanism of the delinquent hopper and supplemental stencil feed device operating mechanism.

Fig. 6 is a detail cross section on the line 6—6 of Figs. 1 and 7, showing the printing and punching mechanisms.

Fig. 7 is a rear view, on an enlarged scale, of a portion of the machine, showing the timing devices for the printing, punching and delinquent hopper mechanisms.

Fig. 8 is a sectional view on the line 8—8 of Fig. 7, showing the timing devices for the printing and delinquent hopper mechanisms, appearing in elevation at the bottom of Fig. 7.

Figs. 9 and 10 are cross sections on the lines 9—9 and 10—10 of Fig. 8.

Fig. 11 is a cross section on the line 11—11 of Fig. 7, showing the punch timing device and operating mechanism.

Fig. 12 is a plan view of the selector head and operating mechanism.

Fig. 13 is a cross section on the line 13—13 of Fig. 12.

Fig. 14 is a section on the line 14—14 of Fig. 7 showing the paper feed mechanism.

Fig. 14a is a detail view of the paper feed roll.

Fig. 15 is a view in diagram of the machine circuits.

Fig. 15a is a detail view showing the selector head and plug-in connections in operative relation to the stencil.

Fig. 16 is a diagrammatic showing of the circuit controlling the paper feed.

Fig. 17 illustrates diagrammatically successive feed steps of the stencils in their passage through the machine.

Fig. 18 shows the relative time periods the circuits are closed in each machine cycle by the selector, and the circuit breakers.

Fig. 19 shows the account form of the address stencil utilized to indicate diagrammatically the plug-in connections from the panel or switchboard of the machine to the selector head to detect debit and credit entries in the account.

Figs. 20 to 24, inclusive and 26, are similar views with different plug-in connections indicated to meet different stencil account conditions.

Fig. 25 shows an address stencil in association with a black stencil blank.

Fig. 25a is a similar showing of a blank orange stencil, and

Fig. 27 shows in full lines the finished label and in dotted lines the perforated edges of the web that are trimmed off.

Referring now to the drawings, the present machine is designed to produce an addressed label 28, of the type shown in Fig. 27, and a debit charge account on each address bearing stencil or device from which a label is printed, examples of which are shown in Figs. 19 to 26.

Across the top of the label, at 21 (Fig. 27) appears the name, etc. of the club, guild or other distributor of books and like publications, for the shipment of which the labels are used. Adjacent the left side of the label, at 22, there is printed information for the postmaster and below that, at 23, the stencilled name and address of the club member or subscriber to whom the labeled book or other publication is to be sent. Excepting the stencilled matter 23, the label blanks are first printed, suitably spaced apart, on a web of paper 24, and wound into a roll or a fan fold ready for use in the machine, which adds only the stencilled name and address to the label blanks. As there is no departure here from

the prior art in pre-printing the blank forms on the web and in mounting the same in roll or other form in the machine or in the provision of the commonly employed slack take-up for the web, guides for carrying it under the stencils in the address printing position to a feed roll and in shearing means for trimming and cutting the labels from the web, a detailed showing and description of this mechanism is not deemed necessary, as the present invention is not limited to the same and may employ other means for accomplishing the same result, if desired.

The web containing the printed label blanks is wider than the finished label, as delivered by the machine, and has a line of perforations 25 along each edge, as shown by dotted lines in Fig. 27, designed to be engaged by pin-like teeth 26 of a roll 27 (see Figs. 14, 14a) by which positive feed of the paper is intermittently advanced in steps of equal length through the machine. In the final operation of the machine, the perforated edges are trimmed off and the labels cut one by one from the web to reduce them to the form shown in full lines in Fig. 27.

The paper feed roll is given step by step rotation to advance the paper in timed relation with the feed of the stencils, by a ratchet 29 and pawl 30 (Figs. 14, 14a). The ratchet 29 is fast on the shaft 31 of the toothed feed roll 27 and the pawl 30 is carried by an arm 32, that is made fast to a pinion 33, loosely mounted on the shaft, the arrangement being such that as the pawl carrying arm 32 is oscillated, motion is transmitted to the feed roll to intermittently advance the paper in steps of equal length. Cooperating with the pinion 33 there is a rack bar 34, which is reciprocated by an eccentric drive 35 from a continuously driven shaft 36, acting through a rod 37, having a pin and slot connection with a bell crank lever 38, pivoted to the rack bar. Cooperating with the bellcrank lever there is a spring latch 39, which yieldingly holds it positioned while the pin 40 idles in the slot 41. The slot is provided at its lower end with a right angular extension 42, in which the pin 40 is normally positioned by the gravitating clockwise tendency of the free end of the slotted rod 37. With the pin in the offset of the slot, motion is transmitted through the bell crank lever 38, rack 34, pinion 33 and ratchet feed 29, 30, to rotate the roll 27, and advance the paper for each operation of the printing mechanism.

As the address printing operation is limited to certain only of the stencils run through the machine, as will be hereinafter explained, provision is made for stopping the feed of the paper during each machine cycle a stencil is passed by the printing mechanism without a label being printed from it. This is accomplished by the action of a solenoid 43 (Figs. 14-16) which, when energized, acts through a spring retracted rocker arm 44, linked to the core 45 of the solenoid, to move the upper end of the slotted rod 37, to the left, as viewed in Fig. 14, to position the pin 40 in the slot proper, where it idles, as the rod is reciprocated by the eccentric drive, thus cutting off transmission of motion to the paper feed.

The circuit of the solenoid 43 (Figs. 6, 16) indicated by leads 46 from a source of supply 47, to ground 48, includes a rotary make and break device 49, mounted on a continuously driven shaft 50 and a self-opening switch 51, of the push-button type, which latter is closed by an engaging extension 52 of the operating arm of the printing

mechanism, hereinafter described, when the arm is inactive or at rest.

With the switch closed, the circuit is completed when the metal segment 49a of the rotor 49b, turning in a clockwise direction, comes in contact with the roller 49c of an arm 49d and the solenoid thus energized, acts to swing the free end of the rocker arm 44 to the left, to shift the pin 40 from the offset 42, into the slot proper, as above described, to cut off transmission of motion to the paper feed roll.

When the operating arm is swung upwardly to operate the printing mechanism, as hereinafter described, and the extension 52 thereof moves clear of the switch 51, the slotted rod 37 and the contact segment 49a of the rotor 49b, are at or near the lower limit of their movement, with the pin 40 idling in the slot 41. After the printing operation is completed and as the operating arm starts to swing downward, the slotted rod 37 reaches the limit of its upward movement, as shown in full lines in Fig. 14 and the solenoid 43 being deenergized, the spring 44a yieldingly holds the free end of the rocker arm 44 clear of the slotted rod 37, permitting the latter to swing to the right and position the pin in the offset of the slot, to reestablish driving relation between the rod 37 and the bell crank for transmission of motion to the feed roll to advance the paper for the next printing operation.

It will thus be seen that the feed of the paper is controlled by the operating arm of the printing mechanism in opening and closing the circuit switch 51 of the solenoid 43. Opening the switch 51 renders the rotary make and break device 49 ineffective and prevents the solenoid from being energized. Closing the switch enables the device 49 to complete the circuit and the solenoid thus energized acts at the critical moment when the eccentric drive rod 37 is at the limit of its upper stroke, with the pin 40 in the offset 42 of the slot 41, to shift the pin into idling position in the slot proper, as previously stated.

In the normal operation of the machine, different stencilled addresses are successively applied to successive label blanks of the web and each stencil or printing device is punched or otherwise marked for each label address printed therefrom, the addressing and punching operations being under the control of the stencils or printing devices in their successive advance through the machine.

The address bearing stencil 53 employed herein (see Figs. 19 to 26) is substantially similar in form to the stencil disclosed in my prior patent referred to, excepting that here the extension 54a of the stencil frame 54, in which the holes 55 are punched, carries the complete account of the club member or subscriber, whose name and address appear in the stencil panel 57. The extension 54a is appropriately charted to serve as an account form 56, covering, in the present instance, a period of two years, in which provision is made for debit, credit and other entries. The numbers 1 to 12 inclusive printed in the square spaces of the two upper cross rows of each section of the account form, represent the twelve months of the year and the blank spaces under the numbered rows are for monthly credit entries in the subscriber's account. The letters R, S, P, R, at the left of the four cross rows of spaces, are the first letters of "Refused," "Shipped," "Paid" and "Returned" and are to be understood as having the meaning of these words, as the following will make clear.

In book clubs and like associations, it is customary in sending out the monthly or other current issue, to accompany it with an announcement of the titles, etc. of one or more books proposed for the next current issue, to enable members or subscribers, if the proposed books are not to their liking, to give notice of their refusal to accept the same. Assuming such notice to be received by the club from a member, as to the book proposed for the next current issue, let us say for October, the member's address-bearing stencil is then hand punched in the tenth square indicated at 58 in the numbered upper row, as shown in Fig. 23, for example, at the left of which row appears the letter R,—the account sign of refused. If then the member fails to approve some other book proposed by the club before the current issue for October is ready for shipment, the presence of the hand punched hole in his address stencil, positioned as described, will permit a circuit to be completed through the hole, in the run of stencils for the October shipment, that will cause that stencil to pass through the machine, without any machine operation upon it, other than to deposit it, according to the condition of the member's account, as shown by previously punched debit and credit entries on the stencil, in either the good or bad account hopper.

Assuming the same advance announcement to a member for the current issue for November, whose acceptance is indicated to the club by its failure to receive notice of his refusal; if the member's account is paid up or if he has not exceeded the limit of credit, as shown, for example, in Fig. 23, by the previously punched holes in his address stencil, the machine circuits completed through such punched holes, will not affect the normal operation of the machine, as to this stencil, in the November run of stencils through the same and an address label will be printed from the stencil for use in shipping the November current issue to the addressee. Following the printing of the address label, and again in the normal operation of the machine, a debit entry will be punched under the space numbered 11, in the second cross row of spaces marked S, the account sign for "Shipped" and thereafter the stencil will be deposited in the hopper for good accounts.

Payments received from members are indicated on the address stencils by hand-punched credit entries in the third cross row of spaces, marked P, the account sign for "Paid" and as such payments are ordinarily made in amounts equalling the charge for one or more books, they cancel one or more of the debit entries in the row above, all of which is detected by the machine circuits in determining the condition of the account, as the stencil is run through the machine.

If, after a book has been shipped to a member, let us say, the current issue for August, and his stencil account has been charged with the shipment by a debit entry hole punched in the space numbered 8 in the second row of spaces, marked S, as shown in Fig. 21, for example, the member is privileged to retain or return the book. Assuming that he decides not to accept it and returns the book within the month preceding the next current issue, his stencil account will be credited, to offset the charge, by a hand-punched hole under the debit entry in the fourth cross row of spaces marked R, the account sign for "Returned." Such balanced entries will have no effect upon the normal operation of the machine,

in the next current run of stencils through the same and, unless the member gives notice of his refusal to accept the next current issue, as above described, the machine will print an address label for its shipment and punch a debit charge for it on his address stencil.

The spaces to the right of the numbered spaces, marked B, and FB, are for account entries for books other than the current monthly issues, above described, such as a "first book," sent to new members or subscribers, for which a charge is made and a "bonus" book, sent free of charge to subscribers whose accounts have been paid up or who have not exceeded the limit of credit for a period of say, six months.

The blank spaces further to the right are for entries by hand, covering special items or sundry charges, etc.

The above described address bearing stencils or devices, representing the mailing list of a book club, guild or other organization, are stacked one above the other in a magazine or hopper 60, located at the right hand end of the machine (see Figs. 1 and 17) and fed one at a time from the under side of the stack by and on each forward stroke of a reciprocating pusher (not shown) to a grooved track 61. The track extends entirely across the machine for the delivery of the stencils to one or the other of two hoppers 62 and 63, at the left hand end of the machine, as viewed in Fig. 1, depending upon the condition of the stencil addressee's account. That is to say, if the stencil account shows that the limit of credit has been exceeded, the stencil is deposited in the hopper 62 for delinquent accounts, but if the limit of credit has not been exceeded, it is deposited in the hopper 63 for good accounts.

The stencils are advanced intermittently in the track across the machine, in steps of equal length, by the action of the reciprocating pusher above mentioned, and, in the operation of the machine, this step-by-step feed action is continuous. As shown in Fig. 1, the direction of feed of the stencils is at right angles to that of the paper and they meet and cross each other in the address printing position, which is the fourth feed step from the stencil magazine 60, as best shown in Fig. 17.

The above method and means for feeding the stencils step by step across the machine, is substantially the same as disclosed in my prior patent referred to, but here a supplemental feed is employed to insure the maintenance of close edge to edge relation between the stencils as they are advanced in the track. This supplemental feed is preferably located, as indicated at 59 in Fig. 1, between the printing and punching mechanisms and consists of a pusher finger 59a (Figs. 3, 4 and 5) fast on a suitably mounted shaft 59b, extending across and above the stencil track. The pusher finger projects downwardly from the shaft into engaging relation with the frame of the stencils in the track and as the shaft is oscillated, the rounded end of the finger, lightly contacting the stencils, urges them forward or in the direction of the main feed.

Accuracy in positioning the stencils is specially important for the punching operation, as the spaces in the stencil account form are small and unless the punched entries are centered in the spaces, the selector pins will not pass freely through them and in binding therein, may fail to close circuits to pre-set the machine for the op-

erations required by the condition of the stencil accounts.

Motion is transmitted from a continuously driven shaft to oscillate the pusher finger shaft, once during each machine cycle, through cam 59c, fast on the shaft, rocker arm 59d, spring retracted rod 59e, crank arms 59f, 59g, on shaft 59h, link 59i, and arm 59j on finger shaft 59b, the arrangement being such that each stencil, on entering the punching position, is given a light forward push, accurately positioning the same for centered action by the punch in the stencil account space to which the punch is adjusted.

In the position taken by an address stencil, in the first feed step from the magazine 60, there is no machine action upon it.

The next feed step, the second from the magazine (see Figs. 1 and 17) brings the stencil into position to be acted upon by a selector (see Figs. 12, 13 and 15a) the general construction and operation of which are substantially the same as the selector disclosed in my prior patent referred to and need not therefore be described at length, except as to detail differences.

The purpose of the selector is to close certain circuits, determined by the punched account entries in the stencils and thereby pre-set the machine, through the operation of time controls, for subsequent action on the stencils.

The selector head 64 (Figs. 12, 13) is provided with a series of openings 65, corresponding in number and spacing with the spaces of the charted account form on the address stencils. These openings (Fig. 15a) are designed to receive the terminals 66, of flexible connections 67, that are plugged in between the selector head and the panel or switchboard 68 of the machine, to connect the selector with various circuits, hereinafter described, controlling the machine operations. The plug terminals project through and below the selector head and are pointed to facilitate entry into the punched holes 55 in the stencils, through which they pass when the head is lowered, to make contact with a metal plate, pan of mercury or other conductor, serving as a common ground 69, for all selector circuits. The selector head is lowered and raised in time with the step-by-step feed of the stencils, to test each one as it is advanced two feed steps from the magazine. The pointed ends of the plug terminals telescope in the usual manner into the socketed body portion of the plugs, and springs within the sockets hold the pointed ends advanced but free to yield when contacting entry spaces of the stencil account form which have not been punched.

The raising and lowering of the selector head is effected in the usual manner by a rack 70 and toothed sector 71 (Figs. 12 and 13) and the latter is given motion through a series of arms and links, by an arm 72, provided with a terminal roller 72a (Figs. 6 and 7) with which a cam 73 cooperates, the cam being carried by an oscillating sector 74, mounted on a shaft 75. A spring 72b acts through the arm 72, to maintain the roller in engagement with the cam.

As an address stencil is advanced beyond the selector or three feed steps from the magazine, there is no machine operation upon it.

The next feed step, four steps from the magazine, brings the stencil into the address printing position, above the paper web and between the printing roll and the platen.

The printing roll 80 (Figs. 1 and 6) is rotatably secured in the usual manner between

forwardly extending arms 81 of the yoke 82 pivoted at 83 to the frame of the machine and is provided with a horizontally elongated passage 84 therein through which the label sheet or web is advanced. The printing roll 80 is supplied with ink through an ink drum 85, from inking mechanism not necessary to describe in greater detail since it may be anything suitable or common in the art. The yoke has a depending arm 86 that is reciprocated by an operating arm 87 to move the printing roll 80 into and out of engagement with the stencils in the stencil track. The operating arm 87, carried by a horizontal shaft 75, mounted beneath the table in brackets 89, is connected with the arm 86 through a link 90. The platen 91 is reciprocated vertically in the usual manner to hold the label sheet in position under the stencil at the time of printing and also to move downwardly away from the stencil to permit the web to be advanced. The reciprocatory movements of the platen are in timed relation with the advance of the stencils to effect a printing operation upon successive stencils when they are stationary in printing position. Since it is desirable to pass selected stencils through the printing position without printing from them, the operating arm 87 has a disengageable connection with the oscillating sector 74 to permit the power mechanism to advance successive stencils without operating the printing mechanism. This disengageable connection (see Figs. 6 and 7) comprises a latch 93 that is pivotally mounted at 94 to the end of the operating arm 87 and has a detent 95 that is adapted to engage a notch 96 of the oscillating sector to connect the arm 87 and sector 74 for conjoint movement. A spring 97 acts upon the latch 93 to normally urge the latch for interlocking connection with the sector 74. Selector operating mechanism controlled by the successive stencils, is provided to effect disengagement of the latch from the oscillating sector to disable the printing mechanism when it is not desired to address a label by a selected stencil. This mechanism includes a vertically extended lever 98 (Figs. 6 and 7) that is pivoted at 99 on a bracket fixed to and depending below the rear edge of the table. The lever 98 has an offset cam extension 100 that cooperates with a cam roller 101 journaled at the end of the latch 93 and so disposed that it can engage the roller and hold the latch detent 95 out of the notch 96 of the sector 74. The lever 98 is connected with a tension spring 102 that normally urges the lever into a position removed from the latch 93 so that the latch can remain engaged with the sector during the oscillating movements thereof. The lever 98, however, can be held normally in a latch disengaging position and thereby in a printing mechanism disabling position. For this purpose the lever 98 at the upper end thereof is provided with a detent 103 which can be arranged to cooperate with a hook 104 releasably carried by a hook holder loosely pivoted on a horizontal shaft 105. In the position shown in Fig. 6, the hook 104 releasably engages the detent 103 thereby holding the cam extension 100 of the lever 98 in latch disengaging position so that the printing mechanism is disabled. The hook 104 can be elevated and thus moved away from engagement with the detent 103, to release the lever and permit the latching of the operating arm 87 and sector 74, for the operation of the printing mechanism. The raising of the hook 104 is effected by a pivoted lever 106 (see

Fig. 7) having the core of a solenoid 107 pivoted near the end thereof remote from the hook. When the solenoid is energized, the core is drawn down and the other end of the lever is raised to elevate the hook from engagement with the lever detent 103. The energization of the solenoid 107 is governed by selector mechanism through the control of the stencils. The solenoid is adapted to be momentarily energized so that the hook after releasing the lever 98 is free to fall and subsequently reengage and again hold the lever when it is re-set. The lever is re-set at each stroke of the sector 74, by means of a cam block 108 carried by the sector and having a cam face 109 at its upper end that is adapted to engage a roller 110 carried by the arm 111 of the lever 98. At each upward stroke of the sector, the cam engages the roller 110 and thereby moves the lever 98 in a clockwise direction and into the reengagement of the hook 104. With the hook as thus described and arranged, a printing operation is effected upon each stencil that permits the circuit to be closed and the solenoid 107 energized.

While the account entry marks of the present machine take the form of punched holes and are preferred, for many reasons, as previously stated, the same result can be obtained by a printed spot of electrically conductive ink or by a thin metal disk stapled or otherwise secured to the stencil. Either of these last mentioned forms would require the use of double contact selector plugs to complete circuits through the marks appearing on one side only of the stencils, but no change other than this would be required in the construction and operation of the machine as shown and described.

The punching mechanism of the present machine is mechanically connected to be pre-set by the address printing mechanism, to punch each stencil from which a label is printed, after the stencil has been advanced two feed steps from the address printing position. Thus connected, the punching mechanism cannot operate upon a stencil the addressing mechanism has passed without printing and remains idle when such stencils become positioned for the punching operation. The connection between the two mechanisms is such that they may operate or remain idle simultaneously, or one may operate while the other remains idle, without interfering with the step-by-step advance of the stencils through the machine but the feed of the paper is stopped, as previously explained, during each period the printing mechanism is idle.

The punch 120 and die 121 are carried by separable sections 122 of a bar-like member 123, which are spaced apart to provide clearance for the stencil track between them, with the punch above and the die below the stencils in the track, as best shown in Fig. 6.

The punch is mounted at the outer end of the upper section of the member 123, which is apertured for the passage of the punch and yieldingly holding the punch flush at the bottom of the opening, there is a spring 124 enclosed in a cylindrical casing 125, which is removably secured in position by screws or bolts. At its upper end, the punch is provided with a flanged head 126 which projects through an opening in the casing, the flange serving as a stop shoulder to limit the action of the spring, which tends to force the punch upward. The die is mounted in the lower section of the member 123 in line with the punch.

The punch-carrying member 123 is adjustable

to set the punch for operation on any one of the squared spaces of the account form of the stencils and as these spaces are comparatively small, accuracy in centering and setting the punch is important for subsequent selector operation and to avoid uncertainty in reading the account.

To facilitate the adjustment of the punch and insure accuracy in the setting, triple guides 127, 128 and 129 are provided, as shown in Fig. 2, which duplicate either the entire space formation of the stencil account or that portion of it over which the punch is adjustable to meet ordinary requirements.

The guide 127 is an exact duplicate of the account form of the stencils and a tapered pointer 130 extending from the punch-carrying member 123 to the guide 127 serves to locate the particular square on the stencil account form in which it is desired to have the punch operate and assists in positioning the punch-carrying member on the other guides 128, 129, where it is secured by headed pins 131 entering openings 132 therein corresponding to the space to which the pointer 130 is adjusted on the guide form 127. This three-point guide adjustment centers the punch and die for operation in the space indicated by the pointer, on the stencil that has been advanced in the stencil track to punching position. As thus adjusted, the punch-carrying member is firmly clamped by a bar 133 and setscrew 134 shown in Figs. 2 and 3.

The punch is operated by a presser head 135 mounted in guides 136 to reciprocate vertically and is provided with a rack bar formation 137 which is engaged by a toothed sector 138. The presser head is dimensioned to cooperate with the punch in any position to which it may be adjusted for operation. Motion is transmitted to the toothed sector to reciprocate the presser head (see Figs. 6 and 11) by an arm 139 made fast to or formed in part with the sector, from which a vertically disposed link 140 extends to a second arm 141 pivoted at 142 and provided with a roller 143 at its free end, with which a cam 144 on a continuously driven shaft 145 cooperates. The connection between the arm 141 and the link 140 is formed by slotting the link at 146 to receive the projecting end of the pin 147 on which the roller 143 is mounted. The slot is elongated vertically to normally permit the pin to idle therein, as it is moved up and down by the cam actuated arm 141 without transmitting motion to the link. A right angle extension 148 is provided at the lower end of the slot and when motion is to be transmitted through the link, to operate the punch, the slotted end of the link is automatically shifted to the left by a time control device, to bring the offset extension of the slot into engagement with the pin.

As previously stated, the punch is pre-set by and in the operation of the printing mechanism, to punch each stencil from which an address is printed, after the stencil has been advanced two feed steps beyond the address printing position. This delayed action is effected by the above mentioned time control device which, in construction and operation, does not differ materially from the "accumulator" of my prior patent referred to and here, as in the patent, these devices are employed to delay successive operations upon the stencil in timed relation to its step-by-step advance through the machine.

As best shown in Figs. 6, 7 and 11, the time control device for the punching mechanism consists of a disk 150 mounted fast on a shaft 151 and

provided with eight equi-spaced pins 152 which are shiftable axially to project from either face of the disk, being yieldingly held as adjusted by springs 153. Normally the disk pins all project from the left face of the disk, as viewed in Fig. 7, and, in cooperation with a cam extension 154 of the link 140, against which they ride, hold the link vertically disposed, with the pin 147 idling in the link slot. The disk 150 is given step-by-step rotation by a ratchet feed, the number and length of the steps per revolution, corresponding to the number and spacing of the pins of the disk. The ratchet feed, best shown in Fig. 6, comprises the usual ratchet 155, mounted on the disk shaft 151 and provided with a tooth for each pin of the disk. A cooperating pawl 157 carried by an arm 158, turning loosely on the shaft, is spring held in engagement with the ratchet and is given motion by an eccentric drive (rod 159 and disk 160) from the power-driven shaft 145.

In each printing operation, the operating arm 87 of the printing mechanism (see Figs. 6 and 7) is given an upward movement and carries with it an extension 162, the cam end 163 of which, cooperating with a roller 164 on the end of a spring retracted rod 165 mounted in bearings 166, moves the rod to the right in opposition to its spring 167, causing it to engage and shift the uppermost pin 152 of the disk 150. As shifted, the pin projects from the opposite face of the disk and thus positioned, will clear the cam extension 154 of the link 140, as the disk is rotated clockwise two steps by the ratchet feed, as viewed in Fig. 11, permitting the link to be swung far enough to the left by a spring 168 to bring the offset portion 148 of its slot 146, into engagement with the pin 147. With the pin thus adjusted in the slot, the link will be moved upward by the cam 144 on the next revolution and, through the arm 139, toothed sector 138, rack 137, and pressing head 135, operate the punch. This adjustment serves for one operation only of the punch and upon its completion, the mechanism returns to normal position.

The repositioning of any disk pin or pins, shifted as above described, is effected by a fixed cam 169 (see Fig. 6) which such pins engage, as the disk is rotated and are pressed inward by it and returned to normal position, projecting from the right side of the disk, as viewed in Fig. 7. The pre-setting of the punch by the printing mechanism for delayed operation, as above described, is repeated for each stencil from which an address is to be printed.

The stencils, after passing through the printing and punching positions, are advanced along the track and deposited in hoppers 62, 63 (Figs. 1 to 4) according to the condition of the stencil account. If the account is in arrears, the stencil is deposited in hopper 62 but if in good condition, in hopper 63.

The stencil track 61 is continuous from the magazine 60 to the entrance to the delinquent hopper 62 and from that point to the hopper 63 for good accounts, there is a separate track section 182, pivoted at 183 to permit the free end thereof, adjoining the main track, to be raised and lowered, as required, to selectively distribute the stencils advanced along the main track into the two hoppers.

Normally, the free end of the pivoted track section 182 is lowered to provide a continuous way for the passage of good account stencils to the hopper 63 being yieldingly held thus by a spring 183a coacting with a member 184, which bridges the track section near its free end, as shown in Figs. 2 and 4. The pivoted track section is raised

to open the hopper 62 for the entrance and deposit therein of stencils of delinquent members or subscribers, by the timed operation of an actuating device, which is pre-set for such stencils by the selector 64, as the stencils are individually tested by it, to determine the condition of the account of the addressees. The action that results in expiring a stencil by causing it to be deposited in the delinquent hopper, is effected by the selector closing a circuit, hereinafter described, through a hole in the stencil, that energizes the "non-print and expire" electromagnet numbered 6 (Fig. 15) by which a second circuit, hereinafter described, is closed to energize the actuating solenoid 185 of one of two timing devices 186, 187, employed for delaying the operation of the expirator seven stencil feed steps from the position in which it is acted upon by the selector.

These timing devices 186, 187, like that above described for pre-setting the punching mechanism for delayed operation, employ similar eight pin disks rotatable step-by-step, by ratchet feeds 189 and 203, but here the disk pins are axially shifted by solenoids 185, 190, acting through pivoted trigger levers 191, 192. A disk pin thus shifted in the timing device 186 acts, three feed steps later, to close the circuit switch 193 of the solenoid 190. When energized, this solenoid shifts a disk pin of the second timing device 187 to engage and give motion, four feed steps later, to a lever 194 that controls the entrance of stencils to the discard or delinquent hopper. The lever 194 (see Fig. 4) pivoted at 195 has one end pivotally connected to the member 184 that bridges the pivoted track section 182 and is provided at its free end with a cam face 196 so shaped that when engaged by a disk pin of the timing device, the free end of the lever will be depressed and the other end elevated to raise the track section and open the discard hopper for entrance of each delinquent account stencil, as it leaves the main track. The disk pins shifted as above described, are reshifted and returned to normal position by being brought into engagement with fixed cams 197, on continued rotation of the disks.

Electric power for operating the various circuits of the machine is obtained from any suitable source of supply, such as a lighting circuit, and is stepped down by a transformer 200 from the usual lighting voltage to a lower voltage for which the electrical apparatus employed is designed.

The normal operation of the printing mechanism, as previously described, is to print an address from each stencil that comes into printing position and the mechanism is set for such operation by control circuits that are automatically closed and opened in timed relation with the step-by-step feed of the stencils through the machine.

To set the printing mechanism for operation, the energizing circuit of a solenoid 107 must be closed by a switch 201 and this is accomplished in the step-by-step rotation of a timing device 202.

When the solenoid 107 is thus energized, it rocks arm 106, releasing latch 104 and freeing arm 98, to permit the pawl 93 of the arm 87, to engage the notch 96 of the sector 14 and connect the arm and sector together to give motion through the link 90 and depending arm 86, to operate the printing roll, as previously described.

The timing device 202, shown diagrammatically in Fig. 15 and in detail in Figs. 7 to 10, is the same as employed in the above described discard hopper and punching mechanisms, and consists of an eight pin disk, rotated step by step by a ratchet feed 203. The disk pins 204 are shifted by a

pivoted trigger lever 205 (see Fig. 7) pivotally connected to the core 206, of a solenoid 208 and are set back or reshifted by a cam plate, as previously described.

The solenoid 208 of the timing device is in a circuit, indicated by leads 209 from the transformer 200 to ground 210, which includes a circuit breaker 213, that operates continuously to make and break the circuit to energize and de-energize the solenoid for each machine cycle. Thus energized, the solenoid 208 shifts a disk pin of the timing device 202 and the shifted pin, two steps later, closes the switch 201 to complete the circuit and energize the solenoid 107 that controls the operation of the printing mechanism. The delay by the timing device in completing the circuit of the print control solenoid 107 permits a stencil to be advanced from the selector position to printing position, where, in the normal operation of the machine, a label is printed from it.

The machine operates, as above described, unless the stencil addressee has exceeded the limit of credit, as shown by his stencil account and, in all such cases, the operation of the machine is modified by control circuits closed by the selector in its test of each stencil account.

The selector control circuits are illustrated diagrammatically in Figs. 15, 15a. The individual conductors plugged in the selector head 64, lead to the junction or switch board 68, as previously stated, as do also the various circuits controlling the printing and the selective distribution of the stencils and by connecting these circuits in preconceived ways, a large variety of different operations of the machine are effected. In order to prevent sparking between the various contact members of the selector circuits, a master circuit breaker 212 is employed in the high voltage line, ahead of the transformer. The relative contact periods of the selector pins and the circuit breakers 212 and 213, for each machine cycle is shown in Fig. 18. The circuit breakers are of well known construction and will not, therefore, be described in detail.

As shown in Fig. 15, provision is made for twelve plug-in connections between the selector head and the junction or switch board, but this number may be varied according to requirements of the use to which the machine is put.

The circuits of plug sockets X, Xa, Xb, and Xc, in the upper row of the switch board, serve to detect debit entries appearing in the stencil accounts and set the machine for appropriate action on the stencils, according to the condition of each account.

The circuits Xa and Xb operate to disable the address printing and punching mechanisms and the circuits X and Xc in addition to disabling the printing and punching mechanisms, operate to expire such stencils as are passed without a label being printed from them, by causing them to be deposited in the delinquent hopper.

In tracing these circuits from the transformer 200 to ground 69, in the order last mentioned above, it will be seen that the two circuits Xa and Xb, while separate and independent of each other, operate to produce identically the same result and that that is also true of the two circuits X and Xc.

The debit circuit Xa, through leads 220 from the transformer 200 to point 221, continues through the winding of the "non-print only" electromagnet 5 to point 222, thence through closed contacts 223 and lead 224 to the plug-in socket Xa of the switch board. A flexible plug-

in connection such as is indicated at 67 continues the circuit from the switch board, through the selector head and it is completed to ground 69, when the selector head is moved downward, by the projecting plug 66 passing through a hole in the address stencil, indicating a debit entry.

The effect of energizing the "non-print only" electromagnet 5 is to break a circuit at point 225 in which the pin-setting solenoid 208 of the timing device 202 is included. Normally, this timing device, in each rotary feed step, operates to close the switch 201 that completes a circuit, indicated by the leads 209 and 227 from the transformer, through the solenoid 107 controlling the operation of the printing mechanism, to ground 228. Failure to complete this circuit, as happens when the "non-print only" electromagnet is energized, leaves the printing mechanism disconnected and disabled and a stencil that is in the addressing position, is passed without a label being printed from it and it is likewise passed without being punched but is deposited in the good account hopper.

The second debit circuit Xb through leads 220 from the transformer 200 to point 221 continues through and energizes the "non-print only" electromagnet 5 and thence to point 222 and on through closed contacts 229 and lead 230 to the plug socket Xb of the switchboard. From the switchboard the circuit is completed to ground 69, as before, by a flexible plug-in connection above described. The effect of completing this circuit to energize the "non-print only" electromagnet, is the same as above stated in the description of circuit Xa.

The third debit circuit X, through leads 220 from the transformer to point 231, thence passes to and energizes the "non-print and expire" electromagnet 6 and thence on to point 232, through closed contacts 233 and lead 234 to the plug-in socket X of the switch board. A plug-in connection continues the circuit from the switch board, through the selector head to ground, as described.

The effect of energizing the "non-print & expire" electromagnet 6 is to break the circuit of timing device solenoid 208 at point 235, to disable the address printing mechanism, as above described, and further, to close contacts 236 and complete a circuit from transformer 200 to ground 210 through leads 209 and 237 and circuit breaker 213, which energizes the solenoid 185 of the expirator timing device 186. When thus energized, the solenoid 185 sets a pin of the timing device 186, and three feed steps later, the pin operates a pushbutton switch 193 to close a circuit, indicated by leads 209 and 238, and ground 239, to energize the solenoid 190 of the supplementary timing device 187. This last mentioned timing device is set by its energized solenoid 190 to act four feed steps later to mechanically operate the expirator, in the manner previously described.

The fourth debit circuit Xc through leads 220 from the transformer, to point 231, continues thence through the "non-print and expire" electromagnet, to a point 232 and on through closed contacts 240, by lead 241 to the plug socket Xc of the switch board. From the switch board, connection through the selector head to ground is made, as above described.

The effect of energizing the "non-print and expire" electromagnet through this circuit is the same as produced through the circuit X, above described, and the description need not, therefore, be repeated.

The circuits of the four plug sockets X', X², X³

and X^4 in the lower row of the switch board, serve to detect credit entries appearing in the stencil accounts.

The circuits X^2 and X^3 , when completed through credit entries offsetting debit entries in the stencil account, operate to counteract the effect of the operation of the debit detecting circuits Xa and Xb , in disabling the printing mechanism and restore the same for normal operation in which labels are printed and the stencils punched.

The circuits X^4 and X' when completed, operate in the same manner to effect the above described result of restoring the printing mechanism for normal operation and, in addition, prevent stencils from being expired by deposit in the delinquent hopper.

The credit circuits X^2 and X^3 , while separate and independent, one of the other, operate to produce identically the same result; credit circuit X^2 counteracting the action of debit circuit Xa and credit circuit X^3 , the action of debit circuit Xb .

Credit circuits X^4 and X' are likewise independent of each other, and operate to produce the same result; credit circuit X^4 , counteracting debit circuit Xc , and credit circuit X' , the action of debit circuit X .

Tracing these circuits in the order just above referred to, the credit circuit X^2 from the transformer 200 to the ground 69 is through leads 220 to point 221 and thence on through electromagnet 1 and lead 221a to the plug-in socket X^2 of the board. From the board to ground 69 is by plugged-in connection through the selector head, as explained in the above description of the debit circuits.

The effect of energizing the electromagnet 1 is to break the debit circuit Xa at point 223 and deenergize the "non-print only" electromagnet when energized through the Xa circuit, as above described, to disable the printing and punching mechanisms.

Credit circuit X^3 from the transformer to ground is by way of leads 220 to point 221 and thence through electromagnet 2, and lead 242 to the plug-in socket X^3 of the switch board. From the board to ground, the circuit is completed as above described.

Energizing the electromagnet 2 breaks the circuit of the "non-print only" electromagnet at point 229 and prevents the printing mechanism from being disabled through the action of debit circuit Xb , the operation and result being the same for this circuit as for credit circuit X^2 , above described.

Credit circuit X^4 from the transformer to ground is by way of leads 220 to points 221, thence through leads 243, electromagnet 3, and lead 244, to the plug socket X^4 of the switch board and from the board to ground, as above described.

Energizing electromagnet 3 breaks the circuit of the "non-print and expire" electromagnet at point 240, thereby preventing any variation of the normal operation of the machine.

Credit circuit X' from the transformer to ground, is by way of leads 220 to point 221, thence through lead 243, electromagnet 4 and lead 245 to the plug-in socket X' of the switch board and to ground, as above described.

Energizing electromagnet 4 breaks the "non-print and expire" circuit at point 233 and otherwise the operation and result are the same as 75

when the electromagnet 3 is energized through circuit X^4 , as above described.

When a bonus run is to be made,—that is, when labels are to be printed for the shipment of bonus books, a blank orange stencil with a single punched hole in the margin (Fig. 25) is inserted next to each address stencil in the file that shows an account condition entitling the addressee to the book. As stacked in the receiving magazine, the orange stencils are above the address stencils they accompany and follow them in their passage through the machine.

The stencil account condition that entitles the addressee to a bonus book must show, let us say, that four current book issues have been paid for during the preceding six months period and, as this excludes from printing, stencils with accounts in arrears, as well as stencils in which the account showing, while failing to meet the bonus book requirements, is such as to entitle the addressees to the next current book issue and for which labels would be printed in the normal operation of the machine, special control circuits are provided for cooperation, through the selector, with the blank orange stencils only and under this rearrangement of circuits, the account formation of the address stencils ceases to exercise effective control and the machine is governed in its operation by the special control circuits above mentioned, to limit the printing to the stencils followed by the orange stencil blanks.

For this special circuit arrangement, referred to, a switch 250 is employed in the circuit indicated by leads 209, the closing of which circuit to energize the print control solenoids 208 and 107, is normally effected in each machine cycle by a circuit breaker 213, when the switch is positioned as shown in full lines in Fig. 15.

Throwing the switch over to the dotted line position (Fig. 15) breaks the circuit 209 at point 251 and makes it at 252, through branch lead 253 to one of two separated contacts 254. The closing of these contacts to complete the circuit 209 and energize the print control solenoids 208 and 107 can only be effected by the action of the "non-print only" electromagnet 5. There is a further departure from the normal circuit arrangement in energizing this electromagnet, in the use of a connection plugged in from switch board socket "02" to a special opening 255 in the selector head (Fig. 12).

The switch board socket "02" and the socket "REF" are connected, as indicated at 256, and utilize the same circuit, to be described later on, to energize the "non-print only" electromagnet. When energized, the electromagnet acts to close the contacts 254 and, with the switch 250 thrown to the dotted line position as described, completes the switch circuit from the transformer 200, through leads 209 and 253, to ground. Included in this circuit is the solenoid 208, which is thus energized and acts, through the timing device 202, switch 201 and solenoid 107, to set the machine to print a label from each address stencil that is advanced to printing position and thereafter punch the stencil and deposit it in the good account hopper.

With the circuits rearranged, as described, the above described operation occurs only when the address stencil is in selector position, with the orange stencil blank following it. The special opening 255 in the selector head, in which the connection from switchboard socket "02" is plugged, is formed in an extension 257 thereof

that projects beyond the selector position, into overlapping relation with the orange stencil blank that follows the address stencil. On the down stroke of the selector head the "62" connection plug in the selector head opening 255 will register with and pass through the opening 253 in the marginal portion of the orange stencil blank 259 (Fig. 26) to complete the circuit from the switch board socket "62" to ground.

After the orange stencil blank has performed its function of setting the machine to print, punch and deposit the stencil it follows, it is advanced to selector position where it is again acted upon by the selector to set the machine for non-print, non-punch and expire operations upon it. This is effected by a connection from the switch board socket "61".

The socket "61" is wired to debit socket X, as indicated at 260 (Fig. 15) the circuit of which and its operation, have been described above, as serving to set the machine for "non-print & expire" and is here utilized for the same purpose when an orange stencil blank comes into selector position. The circuit is completed from the switch board to ground by plugging a connection from socket "61" in a special opening 261 of the selector head, which opening is offset from the main group of openings therein to bring the plug into registry with the specially positioned opening 258 in the orange stencil blank. As set by the circuit completed through the orange stencil blanks, the machine passes them through printing and punching positions without operating upon them and sorts them out and deposits them in the delinquent hopper. They thus serve only for the special bonus runs and are machine-separated from the address stencils, so that the latter are ready for use in the next regular run for the current issue.

The circuit of the switch board socket "REF" from the transformer to ground, is through leads 220 to point 221, thence through the "non-print only" electromagnet to point 222 and on through lead 262 to the "REF" socket. From the socket to the ground is by way of connection plugged in the selector head, as above described.

The effect of closing this circuit and energizing the "non-print only" electromagnet is, as previously described, to set the machine to pass a stencil without printing or punching the same and deposit it in the good account hopper.

The circuit of the switchboard socket, marked "Black," from the transformer to ground, is by way of leads 263 and 220, to point 221, thence through the "non-print only" electromagnet 5, to point 263, and on through lead 264, closed contacts 265 and lead 266, to the switch board. From the switch board to ground the circuit continues through a connection 67, plugged in from the socket "Black" to a specially positioned opening 267 in the selector head (see Figs. 1 and 12) which registers with the single opening 268 (Fig. 25) of the black marker stencil, when the latter comes into selector position.

The effect of closing this circuit is to set the machine to pass the black stencil without printing or punching the same and deposit it in the good account hopper but, under the stencil accounting system herein described, the black stencil marker continues with the address stencil it follows into the hopper in which the latter is deposited.

If the account of the address stencil is not in arrears, the machine will be pre-set to deposit it in the hopper for good accounts and the accom-

panying black stencil will follow it, as above described.

If, on the other hand, the condition of the address stencil account is such as to pre-set the machine to non-print and expire the stencil, it is necessary in that case, to not only pre-set the machine for similar operation upon the accompanying blank stencil, but, in addition, to render ineffective the selector action, in the next machine cycle, in closing the "non-print only" circuit, when the black stencil comes into selector position.

When the "non-print & expire" solenoid 6 is energized by the selector action on the address stencil, as assumed above, the circuit of the solenoid 268 (from the transformer through leads 269) is broken at point 235, and with the solenoid 268 thus rendered ineffective for setting the timing device 262, to close the switch 261, the circuit of the print control solenoid 167, cannot be energized and the printing mechanism is thereby prevented from operating.

In breaking the circuit of solenoid 268, as above described, the "non-print & expire" electromagnet 6 also acts to close the circuit of solenoid 165 (from the transformer through leads 239 and 237 to ground 210) at point 236. When thus energized the solenoid 165 shifts the uppermost pin of the timing device 166, positioning it to engage and give clockwise motion, as viewed in Fig. 10, on its next rotary step, to a pivoted lever 269. This lever acts to break the circuit at point 265, from the switchboard socket "Black," through the "non-print only" electromagnet 5 and close a circuit at point 270, from the "Black" socket of the switchboard through leads 266, contacts 270, lead 271, "non-print & expire" electromagnet 6 to point 231 and on to the transformer by way of leads 220 and 269. The closing of the last described circuit by the selector action upon an address stencil, in pre-setting the machine to non-print and expire the same, also and at the same time pre-sets the machine for the same operation upon a black marker stencil following, so both are deposited in the delinquent hopper.

Assuming the labels are to be printed for shipment of the current book for the month of July, connections would be plugged in between switch board sockets X and X' and selector head openings corresponding to Shipped, Paid and Returned spaces for the month of April in the stencil account form, so that any unpaid account stencil for that month will be passed without being printed and punched and will be expired by being deposited in the delinquent hopper. If, however, there is a hole in the stencil account indicating April Paid or Returned, the stencil will be printed, punched and deposited in the good account hopper. The above described connection from the single switchboard credit socket X' to the two selector head openings Paid and Returned would be made by the branched end of the same wire.

Similar connections would be plugged in between switch board sockets Xc and X⁴ and selector head openings corresponding to "FB" (First Book) Shipped, Paid and Returned in the stencil account form and, depending on whether it has or has not been paid for, the result in the action of the machine on the stencils will be the same as above described. Here again the connection from X⁴ would be branched to plug in selector head openings Paid and Returned.

In addition to the above, a connection would

be made from switch board socket "REF" (Refused) and branched to plug into selector head openings corresponding to July Refused and Shipped spaces in the stencil account form and a further connection from switch board socket "Black" to the offset opening 267 in the selector head, so that any black stencil blanks in the stack will be non-printed or non-printed and expired.

Thus, only those stencils with accounts not in arrears for three months or for first books or which have not been refused, will have labels printed from them for shipment of the current issue for July.

In order that a debit entry may be made for the July shipment in each stencil account from which a label is printed, the punch-carrying member is adjusted on the guides, with the pointer thereof indicating the space numbered 7 in the second numbered row of spaces marked S, (Shipped) in the upper section of the account form and secured as adjusted, thus bringing the punch and die in centered relation, in the corresponding space of the address stencils, as they are successively advanced to punching position in their passage through the machine. The punch, being pre-set by and in each operation of the printing mechanism, for action on each stencil printed form, as above described, will enter a debit charge in the account of each of such stencils for the July book. Selective distribution then follows, the stencils above referred to being deposited in the good account hopper and the others in the delinquent hopper, as above described.

If a record of the number of addresses printed and stencils punched is desired, registering devices 272 of any suitable or well known form may be employed and arranged, as shown in Fig. 1, to be actuated by the printing and punching mechanisms, in each operation thereof. As these devices form no part of the present invention and their use is optional, a detailed description of the same will not be given.

In addition to printing address labels, as above described, the machine is adaptable for like address printing of leaflets announcing new books or containing other matter of interest to club members or subscribers. Such leaflets are ordinarily printed on a web of less width than that employed for labels, and being too narrow for use of the regular feed, a supplementary feed is provided, which is indicated at 284 in Fig. 1. As this supplementary feed may be of any suitable or well known form, it will not be further described.

There is diagrammatically illustrated in Fig. 15, for optional use and forming no part of the present invention, electrical contact devices 285, of well known form and construction, for use in the hoppers and also in connection with the paper web, which act automatically when the entrance hopper is empty and either of the receiving hoppers becomes filled, or the end of the web is reached, to close circuit of a solenoid or the like that operates to throw out a clutch 286 and stop the machine, as is commonly done in the art.

The many important advantages of utilizing address bearing stencils as carriers of the accounts of the addressees and the great economy in time and labor resulting from machine selection in distinguishing between good and bad accounts and from machine-charging such accounts for shipments, machine-addressed from

the stencils, will be apparent from the foregoing without further elaboration.

Having described my invention, I claim:

1. In a label addressing machine in which address-bearing devices and paper to receive impressions therefrom are intermittently fed through address printing mechanism, means for marking each device for each address printed from it, and selective means utilizing the marks to control the operation of the address printing mechanism.
2. In a label addressing machine in which address-bearing devices and paper to receive impressions therefrom are fed step by step through address printing mechanism, means for marking each device for each address printed from it, and means utilizing selected marks to disable the address printing mechanism for operation upon the address bearing devices containing the selected marks.
3. In a label addressing machine in which address-bearing devices and paper to receive impressions therefrom are intermittently fed step by step through address printing mechanism, means for marking each device for each address printed from it, and means utilizing selected marks to complete circuits through the same controlling the operation of the address printing mechanism upon the address bearing devices on which the marks appear.
4. A label addressing machine, as defined in claim 1, in which the operation of the marking means is controlled by the address printing mechanism.
5. A label addressing machine, as defined in claim 1, in which the marking means are preset by the address printing mechanism to operate upon each address-bearing device after a label is printed therefrom and the address-bearing device has passed through the printing mechanism.
6. In a label addressing machine in which address bearing devices and paper to receive address impressions therefrom are intermittently fed through an addressing position, means controlled by the address bearing devices for limiting the address printing to certain only of the devices fed through the machine, and means for punching a hole in each device for each label printed therefrom, the address printing and punching operations being timed to occur simultaneously on different devices and one after the other on the same device.
7. A label addressing machine as defined in claim 1 in which a timing device is interposed connecting the address printing mechanism and marking means for successive operation upon each address bearing device from which a label is printed, the said timing device being set by and in the operation of the address printing mechanism to delay the operation of the marking means for a definite period.
8. In a label addressing machine in which address-bearing devices and paper to receive impressions therefrom are intermittently fed through address printing mechanism, means for marking each device for each address printed from it, and means for completing circuits through the marks of selected address-bearing devices and utilizing such circuits to disable the address printing mechanism for operation upon the aforesaid selected devices.
9. A label addressing machine, as defined in claim 1, in which the address bearing devices are each provided with a charted area representing

an account form and the marks made on the address bearing devices are positioned on the form as dated entries in an account with the addressee.

10. A label addressing machine, as defined in claim 1, in which the address bearing devices are each provided with a charted area representing an account form and the marking means are adjustable to place the mark on the account form at any predetermined point desired.

11. A label addressing machine, as defined in claim 1, in which the address bearing devices are each provided with a charted area representing an account form and the marking means consist of a punch and die relatively positioned for passage of the address bearing devices between 15 the same, the punch and die being adjustable to position the mark on the account form at any predetermined point desired.

12. A label addressing machine, as defined in claim 1, in which the address bearing devices are each provided with a charted area representing an account form over which the marking means are adjustable to place the mark thereon at any predetermined point desired and the address 20 printing mechanism is electrically controlled by 25 circuits completed through the marks.

13. A label addressing machine, as defined in claim 1, in which the address bearing devices are each provided with a charted area representing an account form over which the marking means 30 are adjustable to place marks thereon as desired, the said marking means being connected to the printing mechanism and by it pre-set to follow the operation of the printing mechanism and means controlled by machine selected marks for 35 disabling the printing and marking mechanisms.

14. A label addressing machine, as defined in claim 1, in which each address bearing device is provided with a code formation of an account with the addressee and the marking of such 40 devices for each label printed therefrom appears as a coded charge entry in the account.

15. A label addressing machine, as defined in claim 1, in which each address bearing device is charted for receiving debit and credit entries in 45 an account with the addressee and the marking of such devices for each label printed therefrom appears as a dated entry in the account.

16. A label addressing machine, as defined in claim 1, in which the marks made on the address bearing devices are such as to form a permanent account record, the presence of each mark indicating that an address label has been printed from the device and the position of the mark a dated charge against the addressee.

17. A label printing machine in which address bearing devices and paper to receive address impressions therefrom are fed step by step through address printing mechanism, means for machine marking each address bearing device for each 60 label printed therefrom to serve as debit entries in an account with the addressees, means responsive to such markings for selectively distributing the devices at the end of the passage through the machine and means interposed to follow an 65 address stencil for controlling the operation of the printing, marking and distributing mechanism upon the same.

18. A label addressing machine, as defined in claim 17, in which the operation of the address 70 printing, marking and distributing mechanisms upon selected address stencils is controlled by blank marker stencils interposed to immediately follow the selected address stencils in their passage through the machine.

19. A label addressing machine, as defined in claim 17, in which a blank marker stencil is interposed to immediately follow an address stencil in its passage through the machine and means electrically responsive to the blank marker stencil controlling the operation of the printing, marking and distributing mechanisms upon the address stencil that precedes the blank marker.

20. A label printing machine in which address bearing devices and paper to receive address impressions therefrom are fed step by step through address printing mechanism, means for machine marking each address bearing device for each label printed therefrom to serve as debit entries in an account with the addressee, identifying means interposed to follow selected address bearing devices through the machine, and means responsive to the markings on each of such selected devices for pre-setting the machine for like operations upon it and its accompanying identifying means.

21. A label addressing machine, as defined in claim 17 in which a blank marker stencil is interposed to immediately follow an address stencil in its passage through the machine and means electrically responsive to the blank marker stencil controlling the operation of the printing, marking and distributing mechanisms upon both the address stencil and the blank marker that follows it.

22. A label printing machine as defined in claim 17, in which the interposed device and the address stencil it follows are separated and deposited in different containers by the distributing mechanism.

23. A label printing machine as defined in claim 17, in which the interposed device and the address stencil it follows are deposited by the distributing mechanism in the same hopper.

24. A label addressing machine in which address bearing stencils and paper to receive address impressions therefrom are fed step by step through address printing mechanism and each address bearing stencil is charted for entry of debit and credit items in an account with the addressee, means for account marking each stencil for each label printed therefrom, means for selectively distributing the stencils passing through the machine according to the condition 50 of the account thereon, means electrically responsive to the debit entries in the stencil account for disabling the printing and marking mechanisms, and counteracting means electrically responsive to credit entries in the stencil account 55 for rendering the action of the disabling means upon the printing and marking mechanisms ineffective.

25. A label addressing machine comprising means for advancing a succession of address bearing devices through an address printing position, means for applying the addresses thereof to different sections of a web of paper, means for marking each address bearing device from which an address is printed on the web, means for advancing the web through said printing and marking means, and means for selectively utilizing the marks on said address bearing devices for disabling said address applying and marking means and also for arresting the advance of the web of paper through said address applying means when the latter is disabled.

26. A label addressing machine comprising addressing mechanism including means for advancing a succession of address bearing devices 75 through an addressing position, means for apply-

ing the addresses thereof to different sections of a web of paper provided with equispaced edge perforations, said last mentioned means including a feed roll toothed to engage the edge perforations to advance the paper web through said addressing mechanism, means for marking each address-bearing device from which an address is printed on the web, and means governed by such marks, machine detected on certain of the address-bearing devices, for disabling said address applying means and web feeding means as the devices bearing the detected marks pass through the addressing position.

27. A label addressing machine comprising addressing mechanism including means for advancing a succession of address bearing devices through an addressing position, means for applying successive addresses to successive label sections of a web of paper, means for punching each of said devices for each label printed therefrom, means for advancing the paper web intermittently through said addressing mechanism, means controlled by such punched holes in the address bearing devices for disabling said addressing mechanism, said addressing mechanism having transmission of motion between certain of its parts discontinued when the mechanism is disabled, and associated means responsive to such discontinuance of transmission for simultaneously disabling the web advancing means and the punching means.

28. A label addressing machine comprising addressing mechanism including means for advancing a succession of address bearing devices through an addressing position, means for applying successive addresses to successive label sec-

tions of a web of paper, including a continuously oscillating member, an arm having a latch connection with said member for normally reciprocating therewith, means responsive to selected address bearing devices for unlatching said arm from said oscillating member for effecting the disabling of said addressing mechanism, mechanism for punching each address bearing device from which a label is printed, means for advancing the web intermittently through said addressing mechanism, and means operated by the unlatched arm for effecting the disabling of the punching mechanism and the web advancing means.

15 29. A label addressing machine as defined in claim 28, in which the web advancing means include a feed roll, and means operated by the unlatched arm for discontinuing transmission of motion to the roll.

20 30. A label addressing machine, as defined in claim 28, in which the web advancing means include a feed roll, a continuously operating drive for the roll in which an idling connection is provided, and means controlled by the unlatched arm for discontinuing transmission of motion to the roll by bringing the idling connection into operation.

25 31. A label addressing machine, as defined in claim 28, in which the web advancing means include a feed roll, a continuously operating drive for the roll in which an idling connection is provided, and electrical means, including a switch closed by the unlatched arm, for bringing the idling connection into operation to discontinue 35 transmission of motion to the feed roll.

HARMON P. ELLIOTT.
